BUST CONSTRUCTION FOR GARMENTS

Harry J. Greenberger, Morristown, N. J.

Application September 17, 1946, Serial No. 697,443

5 Claims. (Cl. 2-73)

1

This invention is directed to an improved bust construction for women's garments.

The main object of the invention is to provide a bust construction comprising spaced bust covering parts interconnected by a separately formed central part constituted so that any desired amount of fullness, or cupping, may be obtained in the bust parts while the intervening central part will remain relatively flat. A distinctive tailored appearance and better fit are thus obtained.

A characterizing feature of the new construction involves the formation of the central bust part of the garment in such manner that the opposite sides thereof, to which the inner sides 15 of the bust parts are joined, are each composed of a plurality of angularly related adjoining side edge portions. At least one of the adjoining edge portions at each side are inclined. Preferably, several edge portions at each side are inclined but in opposite relation to one another. It is within the scope of the invention to cut the angularly related edge portions of each side to lie either in outwardly diverging or outwardly converging relation to each other, but a better fit is obtained by arranging such side edge portions in outwardly converging relation.

Through the shaping of the central bust part just explained, the two bust covering parts can be given additional fullness, and their form will be determined by the number and arrangement of edge portions making up each side of the central part to which they are joined.

Preferably, the inner side of each of the bust covering parts are also constituted of a plurality of angularly related adjoining side edge portions, but their angular relation can be different from that of the angular relation of the adjoining side edge portions of the central portion to which they are joined. Further, to give additional fullness, one or more of the inner side edge portions of the bust can be made longer than the corresponding side edge portion of the central bust part to which it is joined and reduced by gathers to the length of the latter edge portion.

The invention will be understood by reference to the illustrative embodiment thereof shown in the accompanying drawing and the detail description thereof to follow.

In such drawing:

Fig. 1 is a fragmentary front view of a woman's slip embodying my new bust construction.

Fig. 2 is a corresponding view showing various fabric parts of the bust construction before assembly.

Located centrally of and preferably integral with the upper end of the garment main fabric body portion 10 and projecting upwardly between the busts is a central bust part 11 the lower ends of which meet the opposite upper edges 12 and 13 60

2

of the garment body. The right side of the central portion is formed as two angularly adjoining upper and lower edges 14 and 15. In the present embodiment the upper edge 14 is inclined downwardly in an outward direction and the lower edge portion 15 is inclined upwardly in an outward direction, the two converging outwardly toward each other and meeting in a point 16 intermediate the height of the central bust part 11. The corresponding upper and lower edge portions 17 and 18 of the left side of the central part are similarly related, but in a reverse sense, converging outwardly towards the left side of the garment and meeting at point 19.

Located on opposite sides of the central bust part 11 are separately formed fabric bust covering parts 20 and 21. The right-hand part 20 has a lower edge 22 joined to the upper edge 12 of the garment body and an inner side joined to the angularly related adjoining side edge portions 14 and 15 of the central bust part. Preferably, and as shown in Fig. 2, such inner side is of different shape than the side of the central bust part in order to provide the desired amount of fullness, or cupping, for the bust. Such inner side is here constituted by angularly related adjoining upper and lower side edge portions 23 and 24 having an angle therebetween somewhat greater than the angle between the side edge portions 14 and 15 of the central bust part. Also, to provide additional fullness in bust covering part 20 upper inner side edge portion 23 is made somewhat longer in length than edge portion 14 to which it is joined and reduced to the length of the latter by gathers 25.

The left-hand bust covering part 21 is formed similarly to right-hand part 20 and includes lower edge 26 joined to upper edge 13 of the main body portion, and an inner side composed of angularly related adjoining upper and lower side edge portions 27 and 28 having an angle therebetween somewhat greater than the angle between side edge portions 17 and 18 of the central bust part 11.

To facilitate the joining of the parts of the garment here above described, a series of notches are provided at suitable points such as notch 29 at the meeting point of the lower end of edge portion 15 of bust part 11 and upper edge portion 12 of main body portion 10, notch 30 at the meeting point of upper and lower inner side edge portions 23 and 24 of bust covering part 20 and notch 31 adjacent the upper end of upper edge portion 23. Notch 31 is intended to be located at the apex 32 of the central bust part when side edge portion 23 is shortened by gathers. The upper marginal portion 33 between notch 31 and edge 34 is folded inwardly to form a hem which may be secured by fancy or other stitching indicated at 35 and 36. The edges 12 and 22, 15 and 24, 14 and 23, 17 and 21, 18 and

28, and 13 and 16 are shown as being joined by further stitching 37. The marginal upper portion 38 is folded upon bust part 20 to form a hem in the same manner as the adjoining upper marginal portion 33. The outer side edge 39 will be joined at the outer side of the garment to a corresponding edge portion of the garment back (not shown). These features in right-hand bust part 20 have their counterpart in left-hand bust part 21. Suitable supporting straps 40 and 41 will be provided to go over the shoulders being secured at their front ends in any suitable manner to the top of bust parts 20 and 21 and being secured at their rear ends (not shown) to the garment back.

It will be understood that the formation of the central bust part 11 with sides comprising angularly related edge portions will serve to cause bust parts 20 and 21 to cup outwardly. By varying the shape of the inner side edges of the bust parts in relation to the shape of the central bust part the amount of cupping can be varied within a considerable range. Additional fullness can also be obtained by providing gathers along the inner sides of the bust parts 20 and 21 as previously explained. Because the bust parts have a natural cupped shape by reason of the fashion construction the central bust part 11 is not distorted when the garment is worn and will maintain its normal substantially flat form.

The particular garment illustrated is a woman's slip. It will be understood that the bust construction may be employed in other women's apparel such as foundation garments, brassieres, and bathing suits, and in any case provides a neat tailored appearance as well as having the functional utility previously explained. The scope of the invention is therefore to be adjudged in accordance with the terms of the accompanying claims.

I claim:

1. A bust construction for garments comprising a central bust part having opposite sides adapted to be located between the breasts, each side including angularly related adjoining edge portions which meet each other at a point intermediate the height of the central bust portion, and a pair of separately formed bust covering parts each having an inner side composed of angularly related adjoining edge portions joined to the angularly related adjoining edge portions of the central bust part at one side thereof, the angularly related adjoining inner side edge portions of each of the bust covering parts being cut to a greater angle therebetween than the angle between the adjoining side edge portions of the central bust part to which they are joined to provide for cupping of the bust covering parts.

2. A bust construction for garments comprising a central bust part having opposite sides adapted to be located between the breasts, each side including angularly related upper and lower edge portions, the upper edge portions converging towards each other in an upward direction, and a pair of separately formed bust covering parts each formed of a single piece of material and each having an inner side composed of angularly related edge portions joined to the angularly related upper and lower edge portions at one side of the central bust part, the angularly related inner side edge portions of each of the bust covering parts being cut to a greater angle therebetween than the angle between the upper

and lower edge portions of the central bust part to which they are joined to provide for cupping of the bust covering parts.

3. A bust construction for garments comprising a central bust part having opposite sides adapted to be located between the breasts, each side including oppositely inclined upper and lower edge portions converging towards each other in an outward direction, and a pair of separately formed bust covering parts each formed of a single piece of material and each having an inner side composed of oppositely inclined upper and lower edge portions joined to the oppositely inclined upper and lower edge portions of the central bust part at one side thereof, the oppositely inclined inner side edge portions of each of the bust covering parts being cut to a greater angle therebetween than the angle between the oppositely inclined upper and lower edge portions of the central bust part to which they are joined to provide for cupping of the bust covering parts.

4. A bust construction for garments comprising a central bust part having opposite sides adapted to be located between the breasts, each side including angularly related adjoining edge portions which meet each other at a point intermediate the height of the central bust part, and a pair of separately formed bust covering parts

each having an inner side composed of angularly related adjoining edge portions joined to the angularly related adjoining edge portions at one side of the central bust part, the angularly related adjoining inner side edge portions of each of the bust covering parts being cut to a greater angle therebetween than the angle between the adjoining side edge portions of the central bust part to which they are joined to provide for cupping of the bust covering parts, and one of the angularly related adjoining inner side edge portions of each of the bust covering parts being of greater actual length than but being reduced by gathers to the length of the side edge portion of the central bust part to which it is joined.

5. A slip comprising a central bust part having opposite sides adapted to be located between the breasts, said opposite sides each being composed of angularly related oppositely inclined, adjoining upper and lower side edge portions converging in an outward direction and meeting each other at a point intermediate the height of the central bust part, the upper side edge portions of the opposite sides converging in an upward direction and meeting at the top of the central bust part, and a pair of separately formed bust covering parts each having an inner side edge composed of oppositely inclined adjoining upper and lower edge portions converging in an outward direction at a greater angle than the angle between the adjoining side edge portions of the central bust part and being joined to the adjoining side edge portions at one side of the central bust part.
